Des. 219,058
Patented Oct. 27, 1970

219,058

BOTTLE RACK

Thomas Paul Kaczur, 342 Whitehorse Pike,
Clementon, N.J. 08021

Filed July 23, 1969, Ser. No. 18,349

Term of patent 14 years

Int. Cl. D7—99

U.S. Cl. D44—29

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 1 is a perspective view of a rack embodying my new design.

FIG. 2 is a front view of the rack shown in FIG. 1.

FIG. 3 is a back view of the rack shown in FIG. 1.

FIG. 4 is a right side view of the rack shown in FIG. 1.

FIG. 5 is a top view of the rack shown in FIG. 1.

FIG. 6 is a bottom view of the rack shown in FIG. 1.

FIG. 7 is a perspective view of another rack embodying my new design.

FIG. 8 is a front view of the rack shown in FIG. 7.

FIG. 9 is a rear view of the rack shown in FIG. 7.

FIG. 10 is a right side of the rack shown in FIG. 7.

FIG. 11 is a top view of the rack shown in FIG. 7; and

FIG. 12 is a bottom view of the rack shown in FIG. 7.

The bottle shown in phantom lines in FIGS. 4 and 10 forms no part of the design but is shown for purposes of illustrating the use of the rack in its intended environment.

I claim:

The ornamental design for a bottle rack, as shown and described.
